UNITED STATES PATENT OFFICE.

JEROME B. ROCKHILL, OF NEW YORK, N. Y.

DESIGN FOR A LIGHT-BULB GUARD MEMBER.

Application filed May 18, 1928. Serial No. 26,730. Term of patent 3½ years.

To all whom it may concern:

Be it known that I, JEROME B. ROCKHILL, a citizen of the United States, and resident of the borough of Manhattan, in the city, county, and State of New York, have invented a new, original, and ornamental Design for a Light-Bulb Guard Member, of which the following is a specification, reference being had to the accompanying drawing, forming a part thereof.

Fig. 1 represents a plan view of the light bulb guard member, showing my new design;

Fig. 2 represents a front elevation of the same;

Fig. 3 represents a side elevation of the same;

Fig. 4 represents a rear elevation of the same; and

Fig. 5 represents a bottom plan view of the same.

I claim:

The ornamental design for a light bulb guard member substantially as shown.

JEROME B. ROCKHILL.
